TENSION DEVICE FOR KNITTING MACHINES

Frederick Scarborough, Rutherford, N. J.

Application August 23, 1945, Serial No. 612,241

13 Claims. (Cl. 66—146)

1
This invention relates to new and useful improvements in tension devices for knitting machines.

More specifically the invention proposes a new and improved tension device which may be used on all types of knitting machines where the yarn is taken from a wound package, more specifically known as a cone of yarn.

During the process of knitting the yarn is removed from the cone at a very rapid pace until the yarn carrier finishes its stroke, completing motion of the machine in one direction. While the machine is in motion in another direction the yarn carrier is in a standing position, and due to the whipping action there is more thread taken from the yarn package than is required, causing the unused portion of the thread to fall back of the present tension limp and uncontrolled. This loose uncontrolled thread is susceptible to formation of loops, or curls which either cause press-offs or imperfections in the knitted fabric. When three carrier attachments are employed, the afore-mentioned difficulties are multiplied and also the possibility of the loose threads becoming entangled with each other. Another fault with the present tension devices is unless provision is made to prevent the loose thread from looping beneath the yarn package, it will result in a press-off.

By the use of the new and improved tension device the thread material will be removed from the yarn cone in a manner that will allow free and even feeding of the thread to the needles.

The present so-called tension wires now in vogue can be removed because they will no longer be required. There is also no further need of the snapper arrangements, this is, of course optional and can be left as a guide of the thread to the carrier position.

It is another object of the invention to so construct the new tension device that any pinching of the thread or yarn will be avoided. It is proposed to provide the tension device with several annular weights through which the thread or yarn passes so that one weight may control slack in the thread between the needles and the tension device, and the other weight or weights may control the slack of the thread between the yarn cone and the tension device. The latter action of this tension device thereby prevents back lashing of the thread which is the common cause of snarls, curls or loops. The danger of loose thread catching under the wound cone is eliminated, and in the use of three carrier attachments of two ends becoming entangled is avoided.

2
Still further the invention proposes a new and improved tension device, as briefly explained, which may be manufactured and sold at a reasonable cost.

5 For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a perspective view of a tension device for knitting machines constructed in accordance 15 with this invention.

Fig. 2 is a horizontal sectional view taken on the line 2—2 of Fig. 1.

Fig. 3 is a vertical sectional view taken on the line 3—3 of Fig. 2.

20 Fig. 4 is a front elevational view of Fig. 1 but illustrated with the thread in a slightly slackened position.

Fig. 5 is a front elevational view of Fig. 1 but illustrated with the thread completely slackened.

25 Fig. 6 is a vertical sectional view taken on the line 6—6 of Fig. 5, illustrated with the thread and weights removed and with one of the parts of the tension device in a raised position.

Fig. 7 is a vertical schematic view showing an optional location of the tension device with respect to a knitting machine.

The new and improved tension device for knitting machines in accordance with this invention includes a body 10, having one or more open compartments 11 which have side walls 12. In the particular design of body shown on the drawings, it is formed from sheet metal, preferably stainless steel. Strips of metal are bent to form the compartments and are soldered, or connected with each other, in any other way. With this construction the compartments 11 are opened at the front as well as at the back. It is essential that the compartments 11 be opened at least at one side so that the interiors are accessible.

40 The body 10 is provided with thread guide elements 14 for guiding the thread or yarn through the compartments 11. These guide elements 14 are in the nature of porcelain eyelets, and they are mounted through the side walls 12 of the compartments.

45 Members 16 are removably mounted upon the body 10 and have spaced arms 17 extending vertically through the compartments 11. These members 16 are in the nature of U-shaped wire members. The top walls of the compartments 11

are formed with spaced openings 18 through which arms 17 pass. The central bends of the members 16 may be used in the nature of handles by which the members may be gripped and pulled upwards free from the body 10. The bottom ends of the arms 17 pass through spaced openings 19 of the compartments 11 formed in the bottom walls of the compartments 11.

Annular shaped weights 20, preferably thermoplastic rings, are slidably mounted on the spaced arms 17 for a thread or threads to pass through, to tension the threads. The bottom walls of the compartments 11 have projecting portions 21 in the vicinity of the openings 19. These projecting portions 21 are bent from the material of the bottom walls of the compartments 11. The bottom ends of the arms 17 engage against the outer faces of the bent portions 21 for frictionally holding the members 16 in a removable condition. The projections 21 have another purpose. They serve to support the annular weights in inclined positions when the weights 20 are free and rest upon the bottom walls of the compartments 11. When the weights 20 are thus supported in inclined positions, they have their top portions projecting upwards and free from contacting with the bottom walls of the compartments 11. For this reason, a thread passing through the weights 20 will not be pinched between the weights and the bottom walls of the compartments. The body 10 is provided with a clip 24 by which it may be conveniently mounted on a support for the tension device.

The operation of the device may be understood from the following:

A thread T is threaded through the eyelets 14 and in between the arms 17 of the members 16 and through the weights or rings 20. When the thread T is tight, the parts will appear as illustrated in Fig. 1. If the thread T slackens slightly, the weights 20 will move downwards as illustrated in Fig. 4, maintaining the tension of the thread T. For this reason, the tension of the thread will be maintained between the cone of yarn or thread and the tension device, and also between the tension device and the needles of the knitting machine. The weights or rings 20 may be properly selected to tension the thread T by their mass. If necessary more than one ring 20 may be used upon each of the pairs of spaced arms 17. In this way the tension of the thread can be controlled.

When the thread T slackens completely, the annular weights 20 will move down and rest upon the bottom walls of the compartments 11. They are now rested upon the projecting portions 21 as illustrated in Fig. 5, and will be held in inclined positions. For this reason, the top portions of the annular weights 20 will be projected upwards out of contact with the bottom walls of the compartments 11. Consequently, thread T cannot be pinched between the weights of the bottom walls of the compartments 11.

The weights 20 may be easily removed and replaced. It is merely necessary to grip any member 16 and pull it upward so that its bottom ends come out of the openings 19. Now the ring or rings 20 are free. Fig. 6 illustrates a member 16 in a raised position. The weights thereof may now be replaced with weights of selected masses.

While I have illustrated and described the preferred embodiments of my invention, it is to be understood that I do not limit myself to the precise constructions herein disclosed and the right is reserved to all changes and modifications com-

ing within the scope of the invention as defined in the appended claims.

Having thus described my invention, what I claim as new, and desire to secure by United States Letters Patent, is:

1. A tension device for knitting machines, comprising a body having open compartment means having side walls, guide elements for guiding a thread or yarn through said compartment means, members removably mounted on said body and having spaced arms extending vertically through said compartment means, and annular shaped weights slidably mounted on said spaced arms for said thread to pass through to tension said thread.

15 2. A tension device for knitting machines, comprising a body having open compartments having side walls, guide elements for guiding a thread or yarn through said compartments, members removably mounted on said body and having spaced arms extending vertically through said compartments, and annular shaped weights slidably mounted on said spaced arms for said thread to pass through to tension said thread, said body comprising strips of metal secured together.

20 3. A tension device for knitting machines, comprising a body having open compartments having side walls guide elements for guiding a thread or yarn through said compartments, members removably mounted on said body and having spaced arms extending vertically through said compartments, and annular shaped weights slidably mounted on said spaced arms for said thread to pass through to tension said thread, said body being provided with a clip by which the tension device may easily be supported.

25 4. A tension device for knitting machines, comprising a body having open compartments having side walls, guide elements for guiding a thread or yarn through said compartments, members removably mounted on said body and having spaced arms extending vertically through said compartments, and annular shaped weights slidably mounted on said spaced arms for said thread to pass through to tension said thread, said guide elements comprising porcelain eyelets mounted through the side walls of said body.

30 5. A tension device for knitting machines, comprising a body having open compartments having side walls, guide elements for guiding a thread or yarn through said compartments, members removably mounted on said body and having spaced arms extending vertically through said compartments, and annular shaped weights slidably mounted on said spaced arms for said thread to pass through to tension said thread, said members comprising inverted U-shaped members.

35 6. A tension device for knitting machines, comprising a body having open compartments having side walls, guide elements for guiding a thread or yarn through said compartments, members removably mounted on said body and having spaced arms extending vertically through said compartments, and annular shaped weights slidably mounted on said spaced arms for said thread to pass through to tension said thread, said members comprising inverted U-shaped members, having their spaced arms passing through openings in the top and bottom walls of said body.

40 7. A tension device for knitting machines, comprising a body having open compartments having side walls, guide elements for guiding a thread or yarn through said compartments, members removably mounted on said body and having spaced arms extending vertically through said compartments, and annular shaped weights slid-

ably mounted on said spaced arms for said thread to pass through to tension said thread, said members comprising inverted U-shaped members, having their spaced arms passing through openings in the top and bottom walls of said body, the bottom walls of said compartments being provided with projecting portions against which the bottom ends of said spaced arms frictionally engage.

8. A tension device for knitting machines, comprising a body having open compartments having side walls, guide elements for guiding a thread or yarn through said compartments, members removably mounted on said body and having spaced arms extending vertically through said compartments, and annular shaped weights slidably mounted on said spaced arms for said thread to pass through to tension said thread, said annular shaped weights comprising thermo-plastic rings.

9. A tension device for knitting machines, comprising a body having open compartments having side walls, guide elements for guiding a thread or yarn through said compartments, members removably mounted on said body and having spaced arms extending vertically through said compartments, and annular shaped weights slidably mounted on said spaced arms for said thread to pass through to tension said thread, the bottom walls of said compartments having projection portions for supporting said annular shaped weights at inclinations with their top portions projecting upwards and free from contacting with said bottom walls, whereby said thread cannot be pinched between said weights and the bottom walls of said compartments.

10. In a tension device for knitting machines, a body having an open compartment with side walls, guide elements for guiding a thread or yarn through said compartment, a member removably mounted on said body and having spaced arms extending vertically through said compartment, and an annular-shaped weight slidably mounted on said spaced arms for said thread to pass through to tension said thread.

11. In a tension device for knitting machines, a body having an open compartment with side walls, guide elements for guiding a thread or yarn through said compartment, a member removably mounted on said body and having spaced arms extending vertically through said compartment,

5 through said side walls. and an annular shaped weight slidably mounted on said spaced arms for said thread to pass through to tension said thread, said guide elements comprising porcelain eyelets mounted

10 12. In a tension device for knitting machines, a body having an open compartment with side walls, guide elements for guiding a thread or yarn through said compartment, a member removably mounted on said body and having spaced arms extending vertically through said compartment, and an annular-shaped weight slidably mounted on said spaced arms for said thread to pass through to tension said thread, said member comprising a U-shaped member having its top portion above the top wall of said body and having its arms extending through openings formed in the top and bottom walls of said body.

15 13. In a tension device for knitting machines, 20 a body having an open compartment with side walls, guide elements for guiding a thread or yarn through said compartment, a member removably mounted on said body and having spaced arms extending vertically through said compartment, and an annular-shaped weight slidably mounted on said spaced arms for said thread to pass through to tension said thread, said member comprising a U-shaped member having its top portion above the top wall of said body and having its 25 arms extending through openings formed in the top and bottom walls of said body, and the bottom wall of said compartment having a projecting portion for supporting said annular weight at an inclination and with its top portion projecting 30 upwards and free from contacting said bottom wall.
